UNITED STATES PATENT OFFICE.

WOOLMAN G. WHITE, OF BROOKLYN, NEW YORK, ASSIGNOR TO INTERNATIONAL
TYPESETTING MACHINE COMPANY, OF NEW YORK, N. Y., A CORPORATION OF
NEW YORK.

LINE-CASTING MACHINE.

1,102,179.

Specification of Letters Patent. Patented June 30, 1914.

Application filed March 20, 1912. Serial No. 685,114.

To all whom it may concern:

Be it known that I, WOOLMAN G. WHITE, a citizen of the United States, residing at Brooklyn, in the county of Kings and State 5 of New York, have invented new and useful Improvements in Line-Casting Machines, of which the following is a specification.

This invention relates to improvements in 10 line-casting machines, and more especially to those of the linotype class, and the primary object of the invention is to provide relatively simple and efficient means whereby single type may be produced simultaneously and in conjunction with the production of the usual lines of type, the casting of the single type as well as the trimming and ejecting thereof being preferably effected by the same mechanisms which perform 15 these functions with respect to the slugs or lines of type, thereby avoiding the necessity of providing duplicate sets of mechanisms as well as simplifying the construction, and also enabling the present invention to be applied directly to linotype 20 machines of the types now in use and without requiring modifications or alterations thereof.

To these and other ends, the invention 25 consists in certain improvements, and combinations and arrangements of parts, all as will be hereinafter more fully described, the novel features being pointed out particularly in the claims at the end of the specification.

In the accompanying drawings:—Figure 1 is a perspective view of a mold wheel, the adjacent vise jaw, and the assembling mechanism as usually employed in the well 30 known linotype machine; Fig. 2 is a front elevation of the upper portion of the mold wheel, showing a single type mold embodying the present invention combined with a line-casting mold as used on linotype machines; Fig. 3 represents a section on the line 3—3 of Fig. 2 showing the relation of the single type mold and its matrix to the fixed vise jaw and the metal pot; Fig. 4 represents a section on the line 4—4 of Fig. 1 40 and showing a multiple letter matrix bar for the single type mold; Fig. 5 is a view, partly in section, showing the mold wheel rotated to ejecting position and showing the ejecting mechanism as well as the galley 45 to receive the line slug and the single type;

Fig. 6 is a detail perspective view of a multiple letter matrix bar such as that shown, for example, in Fig. 4; Fig. 7 is a perspective view of the fixed vise jaw showing a bar provided with a single matrix letter for the 50 single mold; and Fig. 8 is a perspective view of a single type such as that produced by the single mold of the present invention.

Similar parts are designated by the same reference characters in the several views. 65

The present invention provides means whereby a supply of single type such as used, for example, in composing headings and other sorts of work may be produced inexpensively and with facility during the 70 usual operation of line-casting machines and without requiring any special care or attention from the operator.

In the preferred embodiment of the invention, the means for producing the single 75 type is shown combined with the means for producing slugs or lines of type so that each cycle of operations of the machine which casts the slugs, trims and ejects the slugs and serves to effect these same operations 80 with respect to the single type, that is to say, the single type are produced simultaneously and with the same mechanism which produces the line type.

In the present embodiment of the invention, the single type producing means is 85 adapted for application directly to the well known linotype machine and so much of the linotype machine is shown in the accompanying drawing as to enable the construction and operation of single type producing means to be readily understood. The invention, however, is not restricted necessarily to machines of this particular type, and it is to be understood that modifications and changes may be made in the detail construction or in the relative arrangement of the parts in order to enable the invention to be applied to machines of different types and to enable the best results to be obtained. 90

In the present instance, 1 designates the mold wheel which corresponds to the mold wheel of the usual and well known linotype machine and its operation is well known 105 in the art that detail mention thereof is unnecessary. This mold wheel carries a mold 2 which in the present instance corresponds to the mold usually employed for casting slugs or lines of type on the well known 110

linotype machines. The mold has a cavity 3 one side of which is adapted to form a metal receiving connection with the ports 4 of the spout 5, and the opposite side of the mold cavity 3 is adapted to be closed by a line of assembled matrices which are alined and locked between adjustable and stationary vise jaws 6 and 7 respectively. The lines of matrices may be brought to the casting point by any suitable means such, for example, as that usually employed on well known linotype machines, and the metal may be introduced into the mold cavity by mechanism such as that commonly employed for such purpose, the spout 5 in the present instance being contained in the metal pot 8 and the metal may be ejected through the spout by the usual pump or plunger operating in the cylinder 9.

20 To facilitate the application of the present invention to mold mechanism such as that commonly employed on linotype machines, it is preferable to position the line-casting mold 2 in such a manner as to accommodate the single type casting mold at one end thereof, the vise jaw 7 in the present instance having a fixed relation to the end 10 of the line-casting mold.

The means provided in the present instance for producing a single type comprises an auxiliary mold 11 which may, as shown, embody a block formed with a slot 12 which is open at one end of the block and is closed at the other end and the top and bottom of the block, and a slide 13 is adjustable longitudinally of the slot and serves to vary the width or set-way of the single type bodies, the cavity in which the type are cast being in the present instance of a fixed height although as described the mold cavity may be adjusted for type bodies of different widths. The slide 13 may be provided with any suitable means for guiding it properly in its movements, it being shown in the present instance as provided with ribs 14 which slide in corresponding grooves in the block 11 and different means may be provided for setting and retaining the slide 13 at different adjustments, a screw 15 being shewn in the present instance, the stem 16 of which is rotatably fitted in the lower portion of the mold block 11 and the screw cooperates with a threaded surface 17 on the lower edge of the slide 13, an indicator 18 cooperating with the screw to facilitate adjustment of the single mold cavity for the production of single type bodies of different widths. The mold block 11 may be removably held in position on the mold wheel by a relatively fixed support 19 at the bottom and a taper-headed screw 20 which engages a lug 21 on the top of the mold block. This mold for casting single type occupies a position in the same plane with the mold 2 for casting slugs or lines of type and the single

type casting mold is preferably arranged immediately adjacent to one end of the mold 2 as shown, thus enabling the cavity 12 of the auxiliary or single type mold to receive metal from the metal pot through a port 22. 70

The single type, according to the present invention, are cast simultaneously with the casting of the slugs or lines of type and different means may be provided for positioning a matrix at the appropriate end of the cavity of the auxiliary mold. In the present instance, the fixed vise jaw 7 is formed with a groove or recess 23 and this recess is adapted to receive and position a bar or member bearing an appropriate matrix. In Figs. 1, 4 and 6, a matrix bar 24 is shown which bears a plurality of matrices 25 of different characters and this bar is adjustable longitudinally of the groove or recess 23 in the vise jaw and means is provided for setting and positioning the bar with any one of the matrices in co-operative relation with the auxiliary mold cavity. In the present instance, the matrix bar 24 is provided with a number of notches 26 which correspond in number and position to the matrices thereon, and a spring-pressed locking plunger 27 is provided which cooperates with the notches and thereby retains the matrix bar in different set positions. The bar 24 may also be provided at the proper side with an index 28 which bears letters or characters corresponding to the matrices on the bar, and a gage 29 serves to indicate by the scale which matrix character is in co-operative relation with the auxiliary mold cavity. It is, of course, to be understood that the auxiliary mold is in the same plane with the mold which casts the slugs or lines of type and when the spout of the metal pot 105 is in co-operative relation with the line-casting mold, it also cooperates with the auxiliary single type casting mold and, hence, each operation of the machine to cast a line of type serves to cast a single type. The bar 110 30 bearing a matrix character 31 corresponds to the bar 24 in Figs. 4 and 6 except that the bar 30 bears only a single character and it is held in proper position by a relatively stationary projection 32. 115

As usual, in linotype machines, the mold wheel rotates after each casting operation, and this rotation of the mold wheel serves to trim the foot of the slug and to bring the slug into ejecting position. The trimming knife 120 33 serves to trim the slug in the usual way and as the single type is in alinement with the slug, this same knife will trim the single type and continued rotation of the mold wheel will bring the line-casting mold and the auxiliary single type mold into the ejecting position which is illustrated in Fig. 5. The usual ejector slide 34 of the well known linotype machine is shown in the present instance, the ejector blade 35 thereof being 125 130

- positioned to properly register with the mold cavity 3 of the line-casting mold, and this same ejector slide serves in its operation to eject the single type from the auxiliary mold. For this purpose, the mold slide 5 is provided with an auxiliary ejector 36 which is capable of movement longitudinally with respect to the ejector slide and it is capable of being locked in a manner to reciprocate in unison with the ejector slide by 10 a lug 37 on the auxiliary ejector which is adapted to coöperate with a latch 38. When the line-casting and auxiliary molds are in ejecting position, the cavities thereof will register respectively with the ejectors 35 and 15 36 and the operative stroke of the ejector slide will cause the slug and the single type to be simultaneously ejected from their respective molds. The usual galley 39 may be provided to receive the slugs or lines of type, and an auxiliary or supplemental galley 40 may be provided beneath it to receive the single type. A bridge piece 41 may be provided to insure a proper transfer of the 20 single type from the auxiliary mold to the galley 40. The pusher 42 having followers 43 and 44 operates to assemble the lines of type and the single type after delivery to the respective galleys.
- 30 In operation, the mold wheel carrying the line-casting mold and the auxiliary single type mold is brought in the usual manner to the casting point where the line of assembled matrices is presented to one side of the cavity of the line-casting mold and the spout of the metal pot coöperative with the opposite side of the line-casting mold cavity. This same operation serves to position the matrix bar 24 or 30 as the case may be, in operative relation with one end of the auxiliary mold cavity and the same spout of the metal pot in coöperative relation with the opposite end of the auxiliary mold cavity. While the elements occupy such relation, a 40 charge of metal is pumped in the usual manner from the metal pot through the spout thereof and into the line-casting mold and also into the auxiliary single type mold, thereby casting simultaneously a slug or line 45 of composed type and a single type.
- Obviously, by appropriately adjusting the matrix bar 24 or substituting other matrix bars for the bar 24 or 30, as the case may be, single type bearing any selected character 50 may be produced concurrently with the production of the usual slugs or lines of type matter and without in any way interfering therewith.
- After the slug or line of composed type 60 matter and the single type have been cast in the manner stated, the mold wheel is rotated in the well known manner to bring the slug and single type into ejecting position, and during such rotation of the mold 65 wheel, the bases of the slug and the single type are carried past the trimming knife 33 which serves to remove the necks of metal thereon and to properly dress these edges of both the slug and the single type, both operations being performed preferably by the same trimming knife, such being produced in the present instance owing to the location of the line-casting and single type molds in the same plane.
- When the mold wheel is in ejecting position, the slug in the line-casting mold, and the single type in the auxiliary mold are in alignment with the main and auxiliary ejecting blades or members 35 and 36 respectively, and a single operative stroke of the usual 70 ejector slide serves to simultaneously eject the slug and single type from their respective molds and to introduce them into their respective galleys 39 and 40 where they are handled by any appropriate means.
- In order to discontinue the casting of single type when desired, it is only necessary for the operator to release the lug 37 on the auxiliary ejector from the latch 38 and to turn such lug downwardly, whereupon the ejector slide may operate as usual to remove the slugs from the line-casting mold but the previously cast single type will remain in the auxiliary mold, and during the next casting operation, the auxiliary mold will not receive any metal.
- The present invention provides relatively simple and efficient means for casting single type concurrently with the casting of slugs or lines of type, the production of the 80 single type being effected by the operation of the same elements which produce the slugs and, moreover, the single type producing means of the present invention is capable of being applied directly and with 85 facility to line-casting machines of the linotype class, the simplicity of the arrangement, enabling the same to be accommodated on such machines without interfering with any other parts thereof.
- I claim as my invention:
1. The combination of a line-casting mold and an auxiliary mold located in the same plane and operative concurrently therewith to produce single type.
  2. In a linotype machine, a line-casting mold, casting means coöperative therewith, and an auxiliary mold located in the same plane with the line-casting mold and coöperative with said casting means to produce single type.
  3. The combination of means for producing lines of type, and means located in the same plane with the line producing means for concurrently producing single character type.
  4. The combination of a metal pot, a line-casting mold adapted to be positioned in front thereof, and an auxiliary single type-casting mold also adapted to be positioned

in front of the metal pot to receive metal therefrom concurrently with the line-casting mold.

5. In a line-casting machine, the combination of a mold wheel carrying a line-casting mold, casting means, ejecting means, and an auxiliary single type-casting mold on the mold wheel arranged to receive metal from said metal pot and operative upon by

10 said ejecting means.

6. The combination of a mold wheel carrying a line-casting mold and an auxiliary single type-casting mold, casting means common to both molds, and ejecting means

15 also common to both molds.

7. The combination of a mold wheel carrying a line-casting mold and an auxiliary single type-casting mold, casting means common to both molds, trimming means

20 common to both molds, and ejecting means common to both molds.

8. The combination of a line-casting mold, an auxiliary single type-casting mold, casting means for said molds, and ejecting

25 means common to both molds and embodying an ejecting member for the auxiliary mold capable of being rendered inoperative relatively to the ejecting member for the line-casting mold.

30 9. In a line-casting machine the combination of a line-casting mold, an auxiliary single type-casting mold embodying means for adjusting the size of the cavity thereof in one direction, casting means cooperative

35 with said molds, and ejecting means common to and co-operative with said molds.

10. In a machine of the linotype class, the combination of a line-casting mold, an auxiliary mold for producing single type, both

40 molds being in the same plane, a member bearing a matrix character, and means for

positioning such character in co-operative relation with said auxiliary mold.

11. In a machine of the linotype class, the combination of a line-casting mold, an auxiliary mold for producing single type, a member bearing a plurality of matrix characters, and means for setting said member to position any selected character thereon in co-operative relation with said auxiliary

50 mold.

12. In a line-casting machine of the linotype class, the combination of a metal pot, a line-casting mold, a single type-casting mold auxiliary thereto, said molds having

55 openings in the same plane to co-operate with the discharge portion of the metal pot.

13. In a line-casting machine, the combination of a metal pot, a line-casting mold, a single type-casting mold auxiliary thereto, both molds adapted to receive metal from the metal pot, means operative to trim the feet of the type cast in both molds, and ejecting means common to and operative to remove the type from both molds.

14. In a line-casting machine, the combination of a line-casting mold, a single type-casting mold auxiliary thereto, a metal pot common to both molds, a trimming device also common to both molds, ejecting means common to both molds, galleys individual to each mold, and assembling means operative upon the type received by the respective galleys.

In testimony whereof I have hereunto set

75 my hand in presence of two subscribing witnesses,

WOOLMAN G. WHITE.
